UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

EXPANSION SHIELD.

Original application filed August 25, 1921, Serial No. 495,315. Divided and this application filed October 1, 1924. Serial No. 740,901.

To all whom it may concern:

Be it known that I, CHARLES C. TOMKINSON, a citizen of the United States, and a resident of Plainfield, county of Union, and 5 State of New Jersey, United States of America, have invented certain new and useful Improvements in Expansion Shields, of which the following is a specification.

This invention relates to expansion shields 10 for bolt anchors such as are used in walls of brick, stone or cementitious material.

Expansion shields used in bolt anchors in which the shield is expanded by a nut carried by a bolt that bears directly against 15 the bottom of the shield are termed bottom bearing shields. Tests of shields of this type have established the fact that the success of the shield is largely dependent upon the strength of the bottom to resist the pressure 20 of the bolt. When shields of this type are formed from sheet metal the thinness and ductility of the metal makes it desirable to have this bottom end solid and preferable to reinforce the bottom in some manner 25 to withstand this thrust of the bolt.

The object of this invention is to provide an expansion shield made from a single piece of blank of sheet metal which forms 30 an inner end or bottom. Another object is to so construct the shield that its inner or bottom end will be closed. Another object of the invention is to provide a closed bottom shield formed of a single piece of material and requiring no securing means to 35 secure a plurality of sections together. Another object of the invention is to provide a shield that is simple in construction and comprises a single piece stamping. A further object is to provide a reinforcement for 40 the bottom of the shield, which reinforcement may be provided by folds of the metal.

Fig. 1 of the drawings is a plan view of a blank which is to be folded to form the improved expansion shield.

Fig. 2 is an end view of the folded shield made from the blank shown in Fig. 1.

Figs. 3 and 4 are longitudinal sectional views of the inner or bottom portion of the shield, the views being taken at right angles to each other.

Fig. 5 is an elevation of the shield with a bolt and nut therein.

Fig. 6 is a plan view of a sheet metal blank for a modified form of shield.

Fig. 7 is an end view of a shield made 55 from the blank shown in Fig. 6.

Figs. 8 and 9 are longitudinal sectional views of the inner or bottom portion of the shield made from the blank of Fig. 6, the views being taken at right angles to each 60 other.

The blank 10 shown in Fig. 1 is a rectangular piece of sheet metal with notches 11 cut in its longer sides. The central part of the blank, between the notches is bent and 65 folded on the dotted lines indicated generally by the reference numeral 12 in Fig. 1 to form the closed bottom 13 with two double-thickness, substantially triangular reinforcing ears 14 over its outer surface. 70

The end portions of the blank are bent into semi-cylindrical form with opposite edges abutting. This causes the notches 11 to form diametrically opposed triangular openings 15 through the walls of the shield. 75

20 is a tapered nut having wedge projections 21 which extend into the openings 15. 22 is a bolt passing through the nut with its inner end abutting against the bottom of the shield. 80

If desired, the walls of the shield may be indented to form longitudinal ribs 16, the ends of which adjacent the nut may be tapered to fit the nut.

A circumferential groove 17 may also be 85 provided near the outer end of the shield to receive a split ring 18 to assist in holding the parts forming the outer end of the shield together.

When the bolt 22 is turned, the nut moves 90 longitudinally and expands the shield to form a secure anchorage. In doing this, a thrust of the inner end of the bolt against the bottom of the shield is set up and therefore it is important to have the bottom of 95 the shield strong enough to resist this thrust. This is accomplished by making the bottom of the shield of a solid piece of metal which is not distorted or stretched during the formation of the shield, and in the form 100 of shield just described this bottom is strongly reinforced by the ears 14. The solid unperforated bottom also prevents dirt from the hole in which the shield is used from entering the shield and clogging the 105 threads of the nut and bolt.

A simpler form of shield may be made of the blank 30 of Fig. 6, of which the central

- portion 31 is substantially circular with integral rectangular ends 32 extending therefrom. The longitudinal edges of these ends nearest the center are beveled as at 33 to form the wedge shaped openings 34 when the blank is bent and folded into a cylindrical shield. These openings receive the projecting wedges of such a nut as that shown at 20, in Fig. 5.
- 10 The bottom of this shield is solid and is formed of a part of the blank which is not distorted or stretched. If further reinforcement for the thrust of the bolt is desired, a washer 35 may be inserted in the shield 15 under the expanding nut.

The embodiments of my invention herein described are taken from a copending application Serial No. 495,315, filed by me August 25, 1921, of which application this 20 is a division. Other forms may be devised within the spirit and scope of this invention which is defined in the following claims.

What I claim is:

- 25 1. An expansion shield having diametrically opposed portions bent at right angles to the central portion to form laterally expandible sides of the shield and other portions between said opposed portions bent 30 over the central portion.
2. An expansion shield having diametrically opposed portions bent at right angles to the central portion to form sides of the shield and other portions between said 35 opposed portions bent over the central portion and back to the side forming portions.
3. An expansion shield formed of a single piece of sheet metal having its inner end folded double into S shape to form a reinforced bottom.
4. An expansion shield formed of a single piece of sheet metal with the central portion thereof forming a solid closed end, and doubled reinforcing means for said end.
- 45 5. A one piece expansion shield having its inner end closed and folded back on itself.
6. A one piece expansion shield having its inner end closed and having diametrically opposed doubled overlapping portions over 50 its closed end.
7. A one piece sheet metal expansion shield having a central portion forming a closed bottom, and end portions bent from said central portion to fit a cylindrical wall 55 opening, and an expanding member embraced by and contacting with the walls of said shield and movable longitudinally in the shield in contact therewith to expand the shield into permanent gripping engagement in the wall opening.
8. A one piece sheet metal expansion shield having a central portion forming a closed bottom, and end portions bent from 60 said central portion to form a cylindrical shell, the edges of said end portion being

beveled to form wedge-shaped openings in the cylindrical shell, and an expanding member within the shell having wings projecting into said openings.

9. A one piece sheet metal expansion 70 shield having a central portion forming a closed bottom, and end portions bent from said central portion to form a cylindrical shell, the edges of said end portion being notched to form wedge-shaped openings in 75 the cylindrical shell, and an expanding member within the shell having wings projecting into said openings.

10. A one piece sheet metal expansion shield formed of material of uniform thickness and having a central portion forming a closed bottom, and end portions having laterally expandible parallel sides bent from 80 said central portion to form a closed cylindrical shell.

11. A one piece sheet metal expansion shield formed of material of uniform thickness and having a central portion forming a closed bottom, and end portions having parallel sides bent from said central portion to 90 form a closed cylindrical shell, the edges of said end portions being beveled to form wedge-shaped openings in the cylindrical shell, and an expanding member within the shell having wings projecting into said 95 openings.

12. A one piece sheet metal expansion shield formed of material of uniform thickness and having a central portion forming 100 a closed bottom, and end portions bent from said central portion to form a cylindrical shell of single thickness open at its outer end, and an expanding member movable in the shield from one end to the other to laterally expand the shield.

13. In combination, a one piece sheet metal expansion shield bent from a blank of uniform thickness and having a central portion which forms the inner end of the shield, and end portions which form shield side 110 walls of single thickness, said end portions being bent from the central portion into parallelism with each other and transversely curved to fit a cylindrical hole and to leave the outer end of the shield open, and an expanding member adapted to travel longitudinally in the shield and expand the side walls thereof.

14. In combination, a one piece sheet metal expansion shield formed from a blank 120 of uniform thickness having substantially parallel edges, a bent portion forming the inner end of the shield and end portions extending from the bent portion to form longitudinal side walls of single thickness, each wall being transversely curved to fit a cylindrical hole and an expanding member adapted to travel longitudinally in and expand the shield walls and retain the shield walls in expanded relation.

15. In combination, a one piece sheet metal expansion shield formed from a blank of uniform thickness having substantially parallel edges, a bent portion forming the inner end of the shield and end portions extending from the bent portion in parallel relation and forming walls of single thickness, each end portion being transversely curved to fit a cylindrical hole and an expanding member adapted to travel longitudinally in the shield and expand the shield into permanent gripping engagement with the wall of the opening in which the shield is positioned.
16. An expansion shield having walls of uniform single thickness formed from a single piece blank bent to form longitudinally extending, transversely curved, laterally expansible walls, integrally bonded together at the inner end of the shield and an expander for said shield adapted to travel longitudinally within the shield and expand the shield walls into gripping engagement with a wall opening.

In witness whereof, I have hereunto set my hand this 24th day of September, 1924.

CHARLES C. TOMKINSON.
